ASSIGNORS TO HOLCOMB AND HOKE MANUFACTURING COMPANY, OF
INDIANAPOLIS, INDIANA, A CORPORATION.

AMUSEMENT APPARATUS.

1,352,666.

Specification of Letters Patent. Patented Sept. 14, 1920.

Application filed February 25, 1919. Serial No. 279,146.

To all whom it may concern:

Be it known that we, JAMES I. HOLCOMB and JACOB F. HOKE, Jr., citizens of the United States, and residents of Indianapolis, 5 county of Marion and State of Indiana, have invented a certain new and useful Amusement Apparatus; and we do hereby declare that the following is a full, clear, and exact description thereof, reference being had to the accompanying drawings, in which like numerals refer to like parts.

This invention relates to an improved amusement apparatus and is in the nature of a bowling alley of the type generally 15 known as box ball alleys.

The prime feature of the invention is in the provision of movable parts carrying designating numerals for indicating the values of the various alley pins with which 20 they register.

A further feature of the invention is the provision of a back board which normally excludes the numerals and movable parts from view, but which has a plurality of 25 openings therethrough through which the numerals are exposed when elevated.

A further feature of the invention is in pivotally mounting a plurality of alley pins in such manner that when a ball is thrown 30 with force against the lower ends of said pins, they will swing from a vertical to a horizontal position, the lower ends of the pins swinging upwardly, said upwardly moving ends engaging the numeral carrying means and elevating the same so as to expose the numeral thereon through the 35 openings in the backboard.

A further feature of the invention is the provision of anti-friction rollers for 40 cooperating with the numeral carrying means to properly guide the same as they ascend or descend.

A further feature of the invention is the provision of a light and a reflector for 45 diffusing the rays of light directly on to the pins and the numerals when exposed through the openings in the backboard whereby they may be readily read from the forward end of the alley.

50 In the drawings, which are made a part of this application, Figure 1 is a perspective view of a portion of a box ball alley showing the pins and backboard in position thereon. Fig. 2 is a transverse sectional view

through the alley showing the backboard 55 and pins in front elevation, one of the pins being in lowered or knocked down position. Fig. 3 is a similar view of the reverse side of the backboard. Fig. 4 is a sectional view as seen on line 4—4 Fig. 3. Fig. 5 is a detail side elevation of the backboard and parts coöperating therewith. Fig. 6 is an enlarged sectional view as seen on line 6—6 of Fig. 4 and Fig. 7 is a perspective view of one of the numeral carrying members. 65

Referring to the drawings, in which similar reference numerals designate corresponding parts throughout the several views, 1 indicates a box ball alley which may be of the usual or any preferred construction, 70 and 2 indicates a frame structure at the rear end of the alley, said frame carrying a backboard 3 which extends a distance above the alley proper and the lower end thereof being spaced a sufficient distance above the 75 alley to permit balls 4 to easily pass thereunder.

Extending transversely across the alley, between the forward ends of the frame 2 and forwardly of the backboard 3, is a cross 80 bar 5 from which extend a plurality of brackets 6, and pivotally mounted on said brackets are a plurality of alley pins 7, the pivotal connection between said brackets and the pins being at a point below the 85 longitudinal centers of the pins so that said pins will drop by gravity to a horizontal position when the ball 4 is thrown with force against the lower ends of the pins. The pins 7 are normally held in 90 a vertical position by spring latches 8 mounted upon the cross bar 5, the outer ends of the latches entering recesses 9 in the rear face of the pins and snapping over keepers 10 carried by the pins, the blow from the 95 ball releasing the keepers from the latches and permitting the pins to swing on their pivots.

In playing a game, each pin is given a certain value or designating numeral, and in 100 order to prevent confusion as to the value number of each pin that is knocked down, means is provided for exposing the value numeral of the pin when it is moved to a horizontal position and to exclude from view 105 said numerals when the pins are in upright position. To this end a plurality of paddles 11 are placed in the rear of the backboard

3 and are supported by bars 12, said bars having channels 13 in which the paddles slide, and on one face of each paddle is provided a designating numeral 14 which, 5 when the paddle is elevated, registers with and is exposed through an opening 15 in the backboard 3, one opening registering with each independent pin of the alley.

The paddles are so constructed that when 10 the pins are in vertical position, the paddles will descend in the channels a sufficient distance to move the numerals 14 thereon out of registration with the openings in the backboard so that said numerals will not be 15 exposed except when a pin is knocked down, and in order to employ the movement of the pins for elevating the paddles, each paddle is provided with a depending stem 16, which is so positioned that the lower end of the 20 pin, as it is swinging upwardly, will engage the lower flaring end of the stem 16 and move the paddle upwardly a sufficient distance to register the numeral 14 thereon with the opening 15 of the backboard, there- 25 by exposing the numeral to the player and designating the value of the pin knocked down. The downward movement of the paddles is limited by placing a block 17 on the rear face of each paddle at the upper 30 end thereof, which block engages a strip 18 attached to the rear face of the vertical bars 12, thus limiting the downward movement of the paddles.

In order to reduce friction, as the paddle 35 is being raised or lowered, a friction roller 19 is attached to a beam 20 extending across the alley in the rear of the backboard 3, there being a friction roller for each paddle, and to limit the jar and noise incident to 40 the swinging action of the pins, a buffer 21 is attached to the beam 20 so that the lower end of the pin, when swung to horizontal position, will strike said buffer, and as said buffer has more or less cushioning action, 45 the noise and jar incident to the pin striking the same will be limited. The backboard 3 is constructed in any preferred manner and is provided with braces 22 which serve to hold the backboard in upright po- 50 sition, and if desired a light 23 may be attached to the upper end of the backboard.

In order to cast a proper light upon the pins 7 and upon the openings 15 in the back- 55 board so that the numerals exposed there- through may be readily read from the for- ward end of the alley, a reflector 24 may be attached to the forward face of the back- board and over the pins 7, and by placing a light 25 below said reflector, the rays of 60 light will be reflected more directly on to the pins and the openings.

In playing the game, the pins are all thrown to an upright or vertical position and engage with the latches 8 so as to maintain 65 the pins in an upright position. The player

then rolls the ball down the alley in the usual manner, in an endeavor to cause the ball to strike one or more of the pins so as to cause said pin or pins to tilt. As soon as the pin is released from the latch 8, the 70 heavier end of the pin being above its piv- 75 otal point, said pin will swing by gravity to a horizontal position, or until the lower end of the pin strikes the buffer in the rear of the backboard, and as the lower end of the pin moves upwardly it engages the stem portion of the paddle 11 and moves the paddle upwardly, thereby exposing the numeral on the paddle through the opening 15 in the backboard, said numeral designat- 80 ing the value of the pin knocked down. As soon as the prescribed number of balls have been thrown by the player, such pins as are knocked down are again thrown to a ver- 85 tical position and reengaged with the respec- tive latches therefor, when the next player may throw the prescribed number of balls in an endeavor to knock down the pins.

As the pins are returned to their vertical position, the paddles released by such pins, 90 will again descend by gravity and remove the numerals thereon from observation. By thus removing the value designating numer- 95 als from view and maintaining them in such a position until such time as a pin is thrown to a horizontal position, it will be impos- 100 sible to confuse or claim the value for one pin as representing the value of another pin. Furthermore this manner of oper- ating the value indicating numerals lends zest to the game and renders the same more attractive.

The invention claimed is:

1. In an amusement apparatus the com- 10 bination with a plurality of vertically dis- posed pins pivoted adjacent their longitudi- 11 nal center so that their lower ends when struck by a pin ball will move upwardly when pivoting, and a back board having openings therethrough, of numeral carry- 12 ing means operable by the lower portion of said pin when pivoted for bringing the numerals into registration with said open- 13 ings in the back board.

2. In an amusement apparatus the com- 14 bination with a pivot pin normally vertical, the lower end of which when struck by a pin ball moves upwardly when pivoting, and a back board for supporting said pin and having an opening therethrough, of means 15 having a designating numeral thereon, said means being operable by the lower end of said pin to position the numeral in regis- 16 tration with said opening when the pin is struck.

3. In an amusement apparatus the com- 17 bination with an alley, a pin ball rollable thereon, a pivotally mounted pin a back board spaced above said alley to permit the pin ball to pass thereunder and having an 18

- opening therethrough, of a paddle slidably mounted upon said back board and having designating means thereon, the lower end of said paddle being removable from the 5 path of said ball when engaged by the lower and ascending end of said pin when the latter is moved to a horizontal position by the ball, said paddle being movable to register the designating means with the opening in said back board.
4. In an amusement apparatus the combination with a back board having an opening therethrough, a paddle having designating means thereon and a pivotally 15 mounted normally vertical pin, said pin having its lower end adapted to be struck by a pin ball and swing rearwardly and upwardly for engaging and elevating the paddle to register the designating means 20 thereon with the opening in the back board to expose the same when the pin is caused to pivot by the lower end thereof being struck by a pin ball.
5. In an amusement apparatus the combination with an alley and a back board spaced above said alley to permit pin balls to pass thereunder, a paddle vertically slideable upon said board and having designating means thereon adapted to be moved into 25 an exposed position, a pin pivoted adjacent the paddle, the lower portion of the pin when struck by a pin ball being adapted to swing to a substantially horizontal position and lift said paddle to expose said designat- 30
- ing means, and means for limiting the downward movement of said paddle. 35
6. An amusement apparatus including in combination a framework, indicating means slidably mounted in said framework, a pin pivotally mounted on said framework, said pivotal mounting being below the center of gravity of said pin, latching means for normally holding said pin in vertical position and adapted to release said pin when the same is struck below said mounting, the 40 lower and struck end of said pin being movable to a horizontal position to engage the lower end of said slideable means and raise the same, means for limiting the downward movement of said slideable means, and 45 means for cushioning the rearward and upward movement of said pin. 50
7. In an amusement apparatus the combination with a pivot pin normally vertical, the lower end of which when struck by a pin ball moves upwardly when pivoting, and a back board for supporting said pin, of slideable means having designating means thereon, said slideable means being engagable by the lower end of said pin and movable 55 by said pin to an exposed position for exposing the designating means when the pin is struck by a pin ball. 60

In witness whereof, we have hereunto affixed our signatures.

JAMES I. HOLCOMB.
JACOB F. HOKE, JR.
